ROBERT MIEHLE, OF CHICAGO, ILLINOIS, ASSIGNOR TO CONTINENTAL & COMMERCIAL TRUST & SAVINGS BANK, TRUSTEE, OF CHICAGO, ILLINOIS.

BED-MOTION FOR PRINTING-PRESSES.

1,093,346.

Specification of Letters Patent. Patented Apr. 14, 1914.

Application filed July 26, 1911. Serial No. 640,682.

To all whom it may concern:

Be it known that I, ROBERT MIEHLE, a citizen of the United States, and resident of Chicago, in the county of Cook and State of Illinois, have invented a certain new and useful Improvement in Bed-Motions for Printing-Presses, of which the following is a specification.

The invention relates to that class of machines in which a heavy bed or body is reciprocated, as in printing presses in which the "form" is carried upon a bed having a reciprocating movement under the impression cylinder and employing gates to form slots which engage with a crank to stop and reverse the movement of the type bed.

An object of the invention is to provide positive acting means which are free from springs for operating the gates, and for holding the same in proper position at all times.

A further object of the invention is to position the operating mechanism for the gates relative to the bed, so that a large crank stud roller may be used without increasing the normal height of the bed.

These and other objects will in part be obvious, and will in part be hereinafter more fully described.

In the drawings, which show by way of illustration one embodiment of the invention, Figure 1 is a rear side view of a portion of a printing press in elevation, embodying my improvements; Fig. 2 is a rear end view of the same; Fig. 3 is a sectional plan view showing in detail the construction of the gate mechanism for retarding, stopping and accelerating the movement of the type bed; Fig. 4 is a similar view of the gate at one end of the bed closed and in dotted lines the gate opened; and Fig. 5 is a similar view of the gate at the other end of the bed.

In the preferred embodiment as shown, the bed 2 is of the usual flat bed reciprocating type. Fixedly secured to the under side of the bed 2 is a rack frame 1, which is provided with upper and lower racks 3 and 4 with which the driving gear 5 alternately engages. A reversing crank 34 is fixed to the said gear and is provided with a large friction roller 35. The driving gear 5 is secured to the bed motion shaft 6, which extends outside the type bed or press frame, and receives motion from any suitable drive gear, which it is not necessary to describe

herein, as it has no bearing on the present invention.

The driving gear 5 is raised and lowered (thus alternately engaging with the upper and lower racks 3 and 4) by means of the bed motion rocker frame 20', which consists of the fulcrum extensions 16 and 17, which have bearing in the standard 18 and the side frame 15; a bearing 20 (formed on the main body 20') in which is journaled the bed motion shaft 6; an arm 21 (extending from the main body 20' and the bearing 20) which has a stud and friction roller 22 in the cam groove 23 of the bed motion cam 24 on the cam shaft 25. The shaft 25 receives motion in the usual way from a regular train of gears, which it is unnecessary to show in order to understand the present improvement. At one end of the rack frame 1 is hinged a gate 28. Said gate is hinged to upper and lower lugs *a* by studs *b*. The gate is formed with an arm 29 which carries a roller 30. Said gate is also provided with a lug which carries a roller 32. These rollers are positioned to coöperate with face cams 31 and 33 respectively, which cams are mounted on brackets *r* of the framework of the press. Likewise the gate 28' at the other end of the bed is hinged to upper and lower lugs *a'* by studs *b'*. This gate 28' has an arm 29' carrying a roller 30'. A roller 32' is mounted directly on the gate 28'. These rollers 30' and 32' coöperate with similar face cams 31' and 33' carried by the brackets *r*. As the bed is reciprocated, the gates 28 and 28' will be oscillated on their supporting lugs. It will be noted that the cams 31, 31', 33 and 33' all face in the same direction, and are located along one side of the gates, thus giving the entire space below the bed for the height of the gates and the opening cams extend the full length of movement of the gates, so that the gates are constantly under positive control.

The working faces 39 and 39' of the gates 28 and 28', together with the shoulders 40 and 40' of the rack frame 1, form the usual slots in which the crank stud roller 35, on reversing crank 34, operates to retard, stop and reverse the movement of the type bed, in the following manner: Beginning at the position shown in Figs. 1 and 3, in which the type bed is at a stop at the end of the printing stroke, the driving gear 5 being disengaged from both racks 3 and 4, and the

movement of the type bed being controlled by the crank stud roller 35 in the slot formed by the shoulder 40 of the rack frame 1 and the working face 39 of the gate 28. Referring to Fig. 3, the roller 32 against the cam 33' is holding the gate 28 in its closed position, the roller 30 against the cam 31 preventing the working face 39 of the gate 28 from swinging in too close to the rack frame 1. As driving gear 5 rotates in the direction indicated by the arrow, the type bed 2 and the rack frame 1, see Fig. 4, moving to the right on the non-printing stroke, the roller 32 passes over the portion *e* of the cam 33 and the roller 30 passes over the portion *d* of the cam 31, thus positively opening the gate 28 and releasing the said crank stud roller 35. At the same time, the crank stud roller 35 is so released, the driving gear 5 which has been lowered by the movement of the bed motion rocker frame 20', engages lower rack 4 and drives the type bed on the non-printing stroke. The roller 30 acting against the portion *e* of the cam 31, serves to positively hold the gate 28 open, as shown in dotted construction in Fig. 4. The set screw *s* abutting against the gate frame 28, limits the movement of the said gate and prevents the roller 30 from leaving the guide surface *e*. Near the end of the non-printing stroke, as shown in Fig. 5, the roller 32' passes over the portion *f* of the cam 33' and the roller 30', passes over the portion *g* of the cam 31', thus positively closing gate 28', as shown in dotted construction in Fig. 5. The closing of the gate engages the crank stud roller 35, on reversing crank 34, in the slot formed by the working surface 39', and the shoulder 40' of the rack frame 1. At the same time, the said crank stud roller 35 is so engaged, the driving gear 5 is raised by the movement of the bed motion rocker frame 20', thus being disengaged from lower rack 4. The movement of the type bed is now controlled by the crank stud roller 35 in the slot formed as above, and comes to a full stop at the end of the non-printing stroke. As driving gear 5 continues to rotate, and the type bed and rack frame move to the left on the printing stroke, the roller 32' passes over the portion *f* of the cam 33' and roller 30' passes over the portion *g* of the cam 31, thus positively opening the gate 28' and releasing the said crank stud roller 35. At the same time the crank stud roller 35 is so released the driving gear 5 which has been raised by the movement of the bed motion rocker frame 20', engages with upper rack 3 and drives the type bed on the printing stroke. The roller 30' acting against the portion *h* of the cam 31', serves to positively hold the gate 28' open, as shown in Figs. 3 and 5. The set screw *s* butting against the gate frame 28', limits the

movement of the said gate, and prevents the rollers 30' from leaving the guide surface *h*. Near the end of the printing stroke, the roller 32 passes over the portion *c* of the cam 33 and roller 30 passes over the portion *d* of cam 31, thus positively closing the gate 28, as shown in Figs. 3 and 4, and engaging the crank stud roller 35 in the slot formed by the working surface 39 of the gate 28, and the shoulder 40 of the rack frame 1. At the same time, the crank stud roller 35 is so engaged, the driving gear 5 is lowered by the movement of the bed motion rocker frame 20', and thus disengaged from upper rack 3. The type bed is now controlled by the crank stud roller 35 in the slot formed as above, and comes to a full stop in the position shown in Figs. 1 and 3.

It will be noted that the rollers for operating the gates are located on opposite sides of the axis of each gate relative to their direction of movement, and consequently impart a positive opening and closing movement to the gate. The opening cams also extend the full length of movement of the gates, and, therefore, continue to hold the gates open.

The herein improved mechanism avoids the necessity of placing the cams below the line of the crank stud roller, thereby saving room in the height of the press when a large crank stud roller is employed. It will also be readily seen that this improved mechanism not only gives an effective method for operating the gates but one that causes less wear on the parts, is easily adjusted to take up any play due to wear, and, furthermore, one which eliminates the use of springs which formerly were necessary in order to have a strong tension to keep the gates in their proper position at the ends of the stroke when running at high speed, this excessive spring pressure making hard work on the cams, also producing a side strain on the rack frame, which had a tendency to work the type bed out of its true working line. By the simple adjustment of the set screws *s* and *s'*, the rollers 30 and 30' may be kept against the guiding portions *e* and *h* of the cams 31 and 31', thus taking up any play due to wear. The cams, too, are easily adjustable independently of each other, if there be need to put them in alinement, or to take up any play due to wear. This can be done by inserting packing between the brackets *r* and the cams.

It will be obvious that minor changes in the details of construction and the arrangement of the parts may be made without departing from the spirit of my invention.

Having thus described my invention, what I claim as new and desire to secure by Letters Patent, is:

1. A printing press including an impres-

1. A printing press including an impression cylinder, a reciprocated form bed operating in connection therewith, a gate, a crank operating upon said gate for actuating the bed, and means for actuating the gate including a cam for closing the gate, and a cam for opening the gate, said cams being located at one side of the gate. 70
2. A printing press including an impression cylinder, a reciprocated form bed operating in connection therewith, a pivoted gate, means operating through the gate for actuating the bed, means for actuating the gate including a cam for closing the gate, and a cam for opening the gate, said cams engaging the gate structure respectively upon opposite sides of its pivotal axis. 75
3. A printing press including an impression cylinder, a reciprocated form bed operating in connection therewith, a gate carried by the bed, means operating upon the gate for reversing the bed, and means for actuating the gate including a cam for opening the gate, said cam extending substantially the full length of the movement of the gate for positively holding the gate open. 80
4. A printing press including an impression cylinder, a reciprocated form bed operating in connection therewith, a gate carried by the bed at each end thereof, and means operating successively upon the said gates for reversing the bed, and means for actuating the gates including cams operating upon the respective gates for closing the same, and cams operating upon the respective gates for opening the same, all of said cams being located at one side of said gates. 85
5. The combination of a type bed, mechanism for moving said bed, and mechanism for reversing the movements of the bed including a crank, a gate, rollers carried by the gate, a cam for closing the gate, and a second cam for opening said gate, said cams being located at one side of the gate and operated upon respectively by said rollers. 90
6. The combination of a type bed, mechanism for moving said bed, and mechanism for reversing the movements of the bed including a crank, a gate, a cam for closing the gate, and a second cam for opening said gate, said cams having their working faces operating in the same direction and located at one side of the gate. 95
7. The combination of a type bed, mechanism for moving said bed, and mechanism for reversing the movement of the bed including a crank, a gate, a face cam for closing the gate, a second face cam for opening the gate, said cams facing in the same direction, and rollers carried by the gate and operating respectively on said cams. 100
8. The combination of a type bed, mechanism for moving said bed, and mechanism for reversing the movement of the bed including a crank, a gate, a face cam for closing the gate, a second face cam for opening the gate, 105
9. The combination of a type bed, mechanism for moving said bed, and mechanism for reversing the movements of the bed including a crank, a gate hinged to swing about a vertical axis, a cam for closing the gate, a second cam for opening the gate, and devices carried by the gate coöperating respectively with said cams, one of said devices being on one side of said axis and the other device being on the other side of said axis of the gate relative to the direction of movement of the bed. 110
10. The combination of a type bed, mechanism for moving said bed, and mechanism for reversing the movements of the bed including a crank, a gate hinged to swing about a vertical axis, a cam for closing the gate, a second cam for opening the gate, and devices carried by the gate coöperating respectively with said cams, one of said devices being on one side of said axis and the other device being on the other side of said axis of the gate relative to the direction of movement of the bed, said cams and devices being located at one side of the gate. 115
11. The combination of a type bed, mechanism for moving said bed, and mechanism for reversing the movements of the bed including a crank, a gate, a cam for closing the gate, and a second cam for opening said gate, said cams having their working faces operating in the same direction and located at one side of the gate, and a stop for limiting the outward movement of the gate. 120
12. The combination of a type bed, mechanism for moving said bed and mechanism for reversing the movements of the bed including a crank, a gate, rollers carried by the gate, a cam for closing the gate, a second cam for opening said gate, said cams being located at one side of the gate and operated upon respectively by said rollers, and a stop for limiting the outward movement of the gate. 125
13. The combination of a type bed, mechanism for moving said bed, and mechanism for reversing the movements of the bed, including a crank, a relatively large stud roller on said crank, a gate pivoted to swing about a vertical axis, rollers mounted on opposite sides of the axis of the gate relative to its direction of movement, a cam coöperating with one roller for closing said gate, and a cam coöperating with the other roller for opening said gate. 130
14. The combination of a type bed, mechanism for moving said bed, and mechanism for reversing the movements of the bed, including a crank, a relatively large stud roller on said crank, a gate pivoted to swing about

a vertical axis, rollers mounted on opposite sides of the axis of the gate, relative to its direction of movement, a cam coöperating with one roller for closing said gate, and a cam coöperating with the other roller for opening said gate, said cams being located at one side of the gate.

15. The combination of a type bed, mechanism for moving said bed, and mechanism for reversing the movements of the bed, including a crank, a relatively large stud roller on said crank, a gate pivoted to swing about a vertical axis, an arm carried by said gate, rollers mounted respectively on said arm and gate, said arm being shaped so that said rollers are on opposite sides of the axis of the gate; a cam coöperating with one roller for closing said gate, and a cam coöperating with the other roller for opening said gate, said last named cam extending the full length of movement of the gate for positively holding the same open.

16. The combination of a type bed, mechanism for moving said bed, and mechanism for reversing the movement of the bed including a crank, gates coöperating with the crank, a pair of cams arranged at one side of the gates and one above the other for positively opening and closing one of the gates, and a pair of cams located on the same side of the gates and one above the other for opening and closing the other gate.

17. The combination of a type bed, mechanism for moving said bed, and mechanism for reversing the movement of the bed including a crank, gates coöperating with the crank, a pair of cams arranged at one side of the gates and one above the other for positively opening and closing one of the gates, and a pair of cams located on the same side of the gates and one above the other for opening and closing the other gate, all of said cams facing in the same direction and the opening cams extending the full length of movement of the gates.

18. The combination of a type bed, mechanism for moving said bed, and mechanism for reversing the movements of the bed including a crank, a pivoted gate, a roller carried by the gate near one end thereof, a roller carried by the gate near the center thereof, said rollers being located on opposite sides of the pivotal axis of the gate relatively to the direction of movement of the gate, a cam engaging one of said rollers for closing the gate, and a cam engaging the other roller for opening said gate.

In testimony whereof I affix my signature, in presence of two witnesses.
